SKI BINDING

Gerard Rauglas, Great Kills, N. Y.

Application February 23, 1938, Serial No. 191,858

2 Claims. (Cl. 280—11.35)

This invention relates to improvements in ski bindings.

In ski bindings or ski ties the toe irons may be positioned at varying distances apart and at different angles so as to fit shoes of different sizes. The toe irons are adjusted to the proper relative positions to properly fit the shoes of the wearer and are then more or less permanently attached to the skis as by means of screws. It will be appreciated that considerable difficulty is encountered in properly positioning the toe irons so as to fit the shoe of the wearer because positioning of the toe irons must take place prior to the time that it is firmly attached to the ski. Further difficulty is encountered in securing the toe irons to the skis in the desired adjusted positions because in the interval between adjusting the toe irons and securing them to the skis it is difficult to prevent accidental shifting or displacement.

It is a prime object of the invention to overcome the above-outlined difficulties and to provide an improved ski binding in which the toe irons can be readily and conveniently adjusted to the proper relative positions in a minimum amount of time so as properly to fit the shoe of the wearer and can then be firmly secured to the ski without accidental displacement or shifting.

With these and other objects in mind reference should be had to the accompanying drawing in which:

Fig. 1 is a plan view partially broken away, of a ski binding embodying my invention, the ski binding being illustrated as attached to a ski;

Fig. 2 is a sectional view in the direction of the arrows on the line 2—2 of Fig. 1;

Fig. 3 is a sectional view in the direction of the arrows on the line 3—3 of Fig. 1;

Fig. 4 is a plan view of one of the toe irons;

Fig. 5 is a perspective view of one of the lock washers used in connection with my improved ski binding.

Fig. 6 is a sectional view similar to Fig. 2, showing a modified type of ski binding embodying my invention;

Fig. 7 is a plan view of a portion of the modified ski binding; and

Fig. 8 is a perspective view of one of the washers used in the modified type of ski binding.

In the accompanying drawing the numeral 10 designates a ski of conventional construction to which the ski binding 11 is secured.

Referring to the first form of my invention shown in Figs. 1-5 the binding consists of a pair

of toe irons 12 positioned adjacent the two sides of the ski, and a foot plate 14 which aids in properly holding the toe irons in position. The toe irons on the two sides of the ski are mirror images of each other and only one need be described. Each of the toe irons consists of a horizontal portion 15, and a vertical portion 16 disposed at right angles to the horizontal portion. The inner longitudinal edge of each of the toe irons is preferably straight, while the outer longitudinal edge along which the vertical portion 16 is formed preferably tapers inwardly from the rear to the front of the toe iron. The forward and rearward edges of the horizontal portion are preferably rounded or arcuate as shown 17, which permits of the rocking or adjustment of the toe irons when they are assembled beneath the foot plate, as will be more fully described.

To receive the screws or other fastening means to secure the binding to the ski I provide a series of apertures in each of the toe irons, preferably three in number. Thus I provide the slotted apertures 19 and 20 adjacent the forward and rearward edges respectively of each toe iron. I have found that the most satisfactory results are obtained by making the slotted apertures 19 and 20 parallel. Intermediate the slots 19 and 20 I provide another slot 21 extending from the inner edge of the toe irons towards the center thereof and preferably substantially parallel to slots 19 and 20. I prefer to make the slot 21 slightly wider than the other two slots and this slot need not extend as far towards the opposite side of the toe iron as the slots 19 and 20.

The surface of the toe iron adjacent the slot 21 is preferably smooth as shown. To aid in holding the toe irons in accurate, adjusted positions however, the surface adjacent the slots 19 and 20 is serrated as shown at 22, the serrations being formed by a series of parallel alternate ridges and grooves which extend generally transversely of the slots and longitudinally of the toe iron.

The vertical portion 16 of each toe iron may be provided with suitable means such as the slot 23 and the bracket 24 for receiving the straps of the binding. However, these form no part of my invention and other types of strap fastening means may be employed.

In Fig. 4 I show the toe iron which is used on the left side of the ski. In each binding a pair of toe bindings are employed, the other toe iron, which is used on the right side is a mirror image of the one shown in Fig. 4.

The foot plate 14 tapers from the rear to the forward portion thereof as shown and the rear corners are preferably cut away as indicated at 25 so as to provide additional clearance for adjusting the toe irons. The over-all length of the foot plate is preferably slightly greater than the extreme length of the horizontal portion of the toe iron.

In applying my binding to a ski a pair of toe irons are placed opposite each other with the horizontal portions resting on the ski. The foot plate 14 is then placed on top of the horizontal portions of the toe irons as shown. The assembled binding is then held in position by suitable fastening means preferably screws. As has been previously described, the toe irons are provided with slotted openings 19, 20 and 21 which receive the screws. The foot plate 14 is likewise formed with apertures to receive the washers and screws. Thus the toe plate is illustrated as being provided with six apertures, three on each side of the longitudinal center thereof, the forward apertures, which are positioned above the slots 19 of the two toe irons being designated by the numeral 26, the central apertures which are positioned above the slotted openings 21 being designated by the numeral 27 and the apertures at the rear of the plate, which are positioned above the slots 20, being designated by the numeral 28. The openings 26, 27 and 28 are somewhat wider than the slots 19, 20, and 21 and than the screws which are employed to secure the binding to the skis, and they preferably taper from top to bottom and are provided with downwardly depending flanges as shown most clearly in Figs. 2 and 3. Screws of the type shown at 29, having enlarged preferably tapered heads, are employed to secure the binding to the ski. It should be noted that the heads of the screws are somewhat smaller than the apertures 26, 27 and 28, and washers are employed around the heads of the screws so as to prevent the screws from passing through the openings, the washers preferably being provided with tapered side walls corresponding to the tapering walls of the apertures.

The washers that are employed in the forward and rearward apertures 26 and 28 are indicated by the numeral 30 and shown in detail in Fig. 5. The under surfaces of the washers 30 are serrated, being provided with a series of parallel alternate ridges and grooves corresponding to the serrations 22 of the toe irons, so as to form mating engagement therewith when the washers are inserted in the apertures 26 and 28, as most clearly shown in Figs. 2 and 3. It will thus be seen that when the washers 30 are inserted in the apertures 26 and 28 so that the serrations on the under surface of the washers and on the toe irons form mating engagement and the screws 29 are tightly screwed into the skis the binding will be held firmly in position and the toe irons will not be accidentally displaced. In the intermediate apertures 27 I employ washers 32 which are similar to the washers 30, with the exception that the under surface is smooth.

The screws, washers and apertures in the foot plate are so formed that when the parts are assembled as shown, the heads of the screws and 70 the tops of the washers will be flush with the upper surface of the foot plate so as to form a substantially smooth plane surface on the top of the foot plate. The washers however, are of greater thickness than the foot plate so that the lower 75 portions thereof protrude below the foot plate and

engage the upper surface of the horizontal portions of the toe irons.

At its forward and rearward edges, the foot plate 14 is provided with downwardly depending flanges 34 which engage the surface of the ski when the binding is assembled. The longitudinal edges of the plate may likewise be provided with flanges 35 which are smaller than the flanges 34 and only extend to the upper surface of the horizontal portions of the toe irons.

In assembling my improved ski binding on a ski the foot plate 14 with the washers disposed therein may be used as a templet to properly locate the holes for receiving the screws 29. In this connection it will be seen that the foot plate and washers greatly facilitate centering the binding on the ski. A pair of toe irons 12 are then placed in the proper position on the ski, as shown, and the foot plate is positioned in superimposed relation. The washers 30 are placed in the apertures 26 and 28 and the washers 32 are placed in the apertures 27. The screws 29 are then projected through the washers and apertures into the ski. The screws which are positioned in the apertures 27 may be screwed relatively tightly whereas the screws in the apertures 26 and 28 are left relatively loose. The washers 30 are preferably rotated so that the serrations 31 extend transversely of the serrations 22 in the toe irons so as to prevent them from forming mating engagement therewith.

Due to the fact that the screws in the apertures 27 are relatively tight the toe irons will be held relatively firmly. However, it should be remembered that the under surface of each of the washers 32 is smooth and accordingly the toe irons can be shifted towards and away from each other and can be rocked or rotated so as to adjust them to the proper width, the engagement between the washers 32 and the toe irons 12 being sufficient to prevent accidental displacement of the toe irons after they have been properly adjusted and while the binding is being firmly secured to the ski.

To adjust the toe irons the wearer places this ski boot upon the foot plate and the toe irons are then adjusted to the proper width and are rocked or rotated to the proper angle, care being taken that the foot of the wearer is properly centered on the ski at the time that the adjustment is made. The foot of the wearer is then removed from the toe plate and the washers 30 are rotated so that the serrations 31 mate with the serrations 22 on the toe irons. The screws 29 in the apertures 26 and 28 are then screwed tightly in position. It will be appreciated that due to the inter-engagement between the serrations on the washers 30 and the serrations on the toe irons, the ski binding will be firmly held in position on the ski in the desired adjusted position and the toe irons cannot be shifted or displaced without first loosening the screws which extend through the apertures 26 and 28.

Instead of placing the screws 29 and the washers 30 in the apertures 26 and 28 prior to adjusting the toe irons these can be omitted until the adjustment has been completed. If this procedure is followed then the washers 32 are placed in apertures 27 and the screws are driven into the ski relatively tightly at these positions. The toe irons are then adjusted as described above. When they have been properly adjusted the washers 30 are placed in the apertures 26 and 28 so that the serrated lower surface forms mating engagement with the serrations on the toe irons. The screws 29 extending through washers 30 are then

tightly screwed in position so as to firmly hold the toe irons against accidental displacement. It will be seen that the rocking or rotating of the toe irons during their adjustment to fit the shoe of the wearer is permitted by the arcuate forward and rearward edges 17 of the horizontal portions of the toe irons, which provide sufficient clearance between the toe irons and the flanges 34. It will also be seen that the shanks of the screws 29 are narrower than the slots 19, 20 and 21 so as to provide the necessary clearance between the slots and the screws and permit rocking or rotation of the toe irons when they are adjusted.

15 Referring now to the modified form of my invention shown in Figs. 6 to 8 inclusive it will be noted that it consists, as in the first form of my invention, of a pair of toe-irons 12' and a superimposed foot plate 14' corresponding to the 20 toe-irons 12 and foot plate 14 in the first form of my invention. The toe-irons and foot plate are assembled in the same manner and are of similar construction to those shown in the first 25 form of my invention with the exception of the changes as hereinafter pointed out.

The toe-irons 12' in the modified form of my invention are identical with those shown in the first form with the exception that instead of employing the serrations as shown at 22, saw-toothed serrations 36 are employed which face outwardly towards the two sides of the ski binding as shown, so as to resist the outward pressure exerted by the boot or shoe of the wearer against the two sides of the toe irons. The foot plate 14' in the modified form of my invention is likewise similar to the foot plate in the first form of my invention with the exception that the openings 26 and 28 formed therein adjacent the front and rear of the plate are replaced with apertures 40 which do not have downwardly extending flanges as shown at 26', it being understood that similar apertures 26' are formed at both the front and rear of the plate in positions corresponding to the 45 positions of the apertures 26 and 28 in the first form of my invention. Central openings corresponding to and similar in construction to the openings 27 are provided in the plate 14'.

As in the first form of my invention washers 32 having smooth lower surfaces are inserted in the 50 central openings 27. In the opening 26' in the modified form of my invention I employ washers differing from the washers 30 of the first form of my invention as most clearly shown at 37 in Figs. 6 and 8. These washers are provided with central 55 openings as shown, to receive the screws 29, and with a relatively large flat portion 38 for engaging the under surface of the foot plate 14 around the openings and with an upwardly projecting central portion 39 provided with a kerf 40 which projects through the openings 26'. The under surface of the washer is provided with saw-toothed serrations 41 which form mating engagement with the saw-toothed serrations 36 in the toe-irons, so as to firmly resist outward shifting 60 of the toe-irons when the device is assembled as shown in Fig. 6.

So as to facilitate assembling of the device I provide the washer with an outwardly projecting wing 42 which engages with a lug 43, when the 70 serrations 41 are disposed at right angles to the serrations 36. When the saw-toothed serrations are in engagement with each other the wing 42 and lug 43 are disposed at a 90° angle as shown most clearly in Fig. 7.

75 The modified form of my invention is assembled

in a somewhat similar manner to the first form of my invention. Thus the plate 14' with the washers 37 and 32 disposed therein may be used as a templet to properly position the binding in the ski. The toe-irons are then placed in proper position beneath the foot plate. Screws 29 are inserted through the washers and apertures into the ski and the washers 37 are then turned in a counterclockwise direction until the wings 42 engage the lugs 43 and the screws 29 are then 10 tightened so that the washers 37 exert a slight pressure on the toe-irons and so that the washers 32 exert relatively strong pressure on the toe-irons. It will be appreciated that the serrations 41 are then disposed at right angles or transversely to the serrations 36 so as to permit of limited movement between the toe-irons and foot plate. The boot or shoe of the wearer is then properly positioned in the binding and the toe-irons are adjusted as desired. The toe-irons can 15 be moved sideways and rocked to the desired position so as to perfectly grip and hold any type of boot or shoe. The boot or shoe can easily be removed without disturbing the adjustment of the toe-irons, due to the pressure exerted by the 20 washers upon the toe-irons. 25

After the boot or shoe has been removed the washers 37 are turned in a clockwise direction until the saw-toothed serrations 41 engage the saw-toothed serrations 36. The screws 29 are 30 then screwed tightly in position and it will be appreciated that the toe-irons will be firmly held against accidental displacement. When the skis are in use the boot or shoe of the wearer exerts outward pressure upon the toe-irons 12'. 35 Due to the saw-toothed serrations arranged as shown and described, accidental shifting or displacement of the toe-irons will be effectively prevented. It will be seen that both the kerf 40 and projection 42 serve as indicators to indicate 40 visually and to the touch respectively the relative position of the serrations on the under surface of the washer.

From the foregoing description of my invention it will be appreciated that I have provided 45 an improved ski binding in which the toe irons can be readily and conveniently adjusted to the desired relative positions and then can be readily secured in position on the ski so as to be held against accidental displacement. It should be 50 understood that modifications may be made in the illustrated and described embodiment of my invention without departing from the invention as set forth in the accompanying claims.

55 I claim:

1. A ski binding comprising a pair of toe-irons each having a vertical shoe engaging portion arranged in confronting relationship, and a horizontal portion adapted to rest on the upper surface of the ski, the horizontal portion of each toe-iron being provided with elongated slots to aid in attaching the toe-irons to the skis and the surface of the horizontal portion being provided adjacent the slots with serrations; a foot plate positioned in superimposed relation over the horizontal portions of the toe-irons and formed with apertures positioned in registry with the slots in the toe-irons; washers positioned in the apertures in the foot plate having serrations on the lower surface mating with the serrations on the toe-irons and formed with an annular ledge for engaging the under-surface of the foot plate; and fastening means adapted to extend through the washers and slots for securing the binding to a ski. 60 65 70 75

2. A ski binding comprising a pair of toe-irons each having a vertical shoe engaging portion arranged in confronting relationship, and a horizontal portion adapted to rest on the upper surface of the ski, the horizontal portion of each toe-iron being provided with elongated slots to aid in attaching the toe-irons to the skis and the surface of the horizontal portion being provided adjacent the slots with serrations; a foot plate 10 positioned in superimposed relation over the

horizontal portions of the toe-irons and formed with apertures positioned in registry with the slots in the toe-irons; washers positioned in the apertures in the foot plate having serrations mating with the serrations on the toe-irons and formed with indicating means for indicating the relative position of the serrations; and fastening means adapted to extend through the washers and slots for securing the binding to a ski. 5

GERARD RAUGLAS. 10
